UNITED STATES PATENT OFFICE.

JOHN W. DOUGLASS, OF PHILADELPHIA, PENNSYLVANIA, ASSIGNOR TO PROTECTIVE
"FREFLO" STOPPLE COMPANY, OF DOVER, DELAWARE, A CORPORATION OF DELA-
WARE.

DESIGN FOR A BOTTLE-NECK VALVE MEANS.

46,799.

Specification for Design. Patented Dec. 29, 1914.

Application filed July 18, 1914. Serial No. 851,835. Term of patent 14 years.

To all whom it may concern:

Be it known that I, JOHN W. DOUGLASS, a citizen of the United States, residing at Wynnefield, in the city and county of Philadelphia, and State of Pennsylvania, have invented a certain new, original, and ornamental Design for a Bottle-Neck Valve Means, of which the following is a specification, reference being had to the accompanying drawings, forming part hereof, in which—

Figure 1, is a plan view of the dish-shaped recessed top of valve-plug means embodying one of the particular features of my new design. Figs. 2 and 3, are respectively, elevational views, showing the semi-circular recesses in the body of the plug-means, located between reversely arranged wide rounded

surface peripheral ribs of the said body and embodying other particular features of my said new design; and Fig. 4, is an underneath plan view of the peculiarly tapered base of the valve-plug means, and in part merged with the semi-circular recesses of said body for a definite purpose and embracing certain other features of design of my said invention.

I claim:—

The ornamental design for a bottle-neck valve means as shown and hereinbefore described.

JOHN W. DOUGLASS.

Witnesses:

THOMAS M. SMITH,
ROSE E. SMITH.
